UNITED STATES PATENT OFFICE.

MATTHEW HOWARD REED, OF AVALON, PENNSYLVANIA.

COIN-CONTROLLED WEIGHING APPARATUS

No. 831,240.

Specification of Letters Patent.

Patented Sept. 18, 1906.

Application filed July 14, 1904. Serial No. 216,529.

To all whom it may concern:

Be it known that I, MATTHEW HOWARD REED, a citizen of the United States, residing at Avalon, in the county of Allegheny and State of Pennsylvania, have invented certain new and useful Improvements in Coin-Controlled Weighing Apparatus, of which the following is a specification, reference being had therein to the accompanying drawings, forming a part of this specification, in which—

Figure 1 is a vertical sectional view through the operative portion of my invention, showing the inclosed mechanism in elevation in its normal inoperative position. Fig. 2 is a detail sectional view, on an enlarged scale, indicated by the line II II of Fig. 1. Fig. 3 is a similar sectional view indicated by the line III III of Fig. 1. Fig. 4 is a view similar to Fig. 1, showing the mechanism in the position assumed in operation when actuated by a coin. Fig. 5 is a vertical sectional view indicated by the line V V of Fig. 1. Fig. 6 is a similar view indicated by line VI VI of Fig. 1. Fig. 7 is a detail view illustrating the combination, with the poise-beam, of a plunger and dash-pot. Fig. 8 is a detail face view detached of the scissor-arms and their locking and unlocking coin-controlled mechanism adapted to engage the variable counterpoise. Fig. 9 is a view in front elevation, showing the complete apparatus. Fig. 10 is a detail view in perspective, showing the baffle-plate connected with the variable counterpoise in relation with the delivery end of the coin-chute. Fig. 11 is a horizontal detail sectional view indicated by the line XI XI of Fig. 1.

My invention consists of an improved coin-controlled weighing apparatus having for its object to register the weight of the operator upon depositing a coin of proper denomination within certain predetermined limits, provided with selective mechanism arranged to be adjusted by the operator, coin-released indicating devices adapted to show within a certain range the accuracy of the selection, and means for retaining or returning the coin dependent on the degree of movement of said indicating devices.

Referring to the drawings, 2 is a platform-scale of usual construction provided with scale-levers, &c., and a steelyard-rod 3, extending up through a hollow post 4, on which is mounted the case or housing 5, within which is contained the mechanism of my in-

vention. The steelyard-rod 3 is connected with a steel lever 6, which in turn is connected by rod 7 with one end of a poise-beam 8, hung in the usual manner and provided with a poise 9.

10 is a variable counterpoise pivotally suspended by a hook 11 from the outer end of beam 8, fulcrumed at 12 at the extremity of rigid anchor loop or hook 13 and provided with a terminal point 14. This variable counterpoise is adapted to point to zero when the poise 9 is set to the exact weight of the operator; but to indicate upon a dial 15 more or less than said indicated weight within limits corresponding to the number of pounds, more or less, that the weight of the operator exceeds or falls short of the weight indicated by the poise.

The variable counterpoise is normally maintained at zero, as in Fig. 1, by scissor-arms 16 16, pivoted at 17 to a stationary pin-bearing adapted to close together under action of spring 18 and bear at both sides against a pin 19, secured to the counterpoise 10, thus centering it, the arms also abutting against a limiting-stop 20. 21 is a coin-chute registering with an insertion-opening 22, an intervening gate 23 being pivoted at 24 and provided with a portion extending out into range of a closing-door 25, forming a portion of the front of case 5. (See Fig. 11.) When the door is closed, the slot is open, but when the door is open the gate closes the slot, preventing operation of the machine. By this means the device cannot be operated until the door is closed.

26 is a vertically-movable bar adapted to be depressed by a latch 27, pivoted to the extremity of an arm 28 and engaging pin 29 abutment 29 on bar 26 to throw it down when the door is closed, the arm 28 swinging around and drawing the latch 27 off of the pin after it has been sufficiently depressed. At the proper point of depression a lug 30 on bar 26 is engaged by a latch 31 on locking-lever 32, pivoted at 33, pressed upward by spring 34, and extending out underneath the end of the poise-beam. When the weight of the operator is removed, the beam falls, striking lever 32 and releasing bar 26, which is then thrown up by spring 35, engaging the arm 36, pivoted at 37. Springs 18 are mounted on arm 36, and when the arm rises these springs exert pressure upon the scissor-arms 16 to close them and cause the counterpoise 10 to assume the zero position.

On return or downward movement of the bar the scissor-arms are pulled apart by the springs, thus permitting the variable counterpoise to operate through its range of movement when released, as hereinafter described.

38 is a movable coin-chute pivoted at 39, provided with a locking-trigger 40, adapted to enter recesses 41 in the back ends of arms 16, as in Fig. 1, so as to hold these arms closed. The coin-chute 38 extends into the path of chute 21 and is so balanced that the weight of the coin depresses it, as in Fig. 4, throwing the trigger out of the notches and 15 unlocking the mechanism. Chute 38 in turn delivers into a chute 42, the end of which terminates above the money-drawer 43.

44 is a baffle-plate suspended from counterpoise 10 and provided with a slot 45 of sufficient length to register with the end of chute 42 when the counterpoise is at zero or, say, within one pound of it either way. Within these limits it will be seen that the coin will pass through said opening and out 25 through channel 46 and opening 47 in the front of the case, being thus returned to the operator. In other cases, however, the coin will strike the baffle-plate above or below its slot and will be thrown back into the money-drawer and retained.

If desired, other means may be employed to interfere with and retain the coin when the predetermined range of movement is exceeded and to allow free passage of the coin 30 to the exterior when said limit is not exceeded, and it will be understood that I do not desire to be confined to the exact means which I have shown and described for this purpose.

40 It is obvious also that the mechanism may be so constructed that the coin will always be retained, as by omitting the slot from the baffle-plate or by merely interposing the money-drawer in the path of the coin 45 from the chute 42, so as to receive it at all times.

For the purpose of preventing fraudulent use of the machine, as by another person getting on the scale, after one has been 50 weighed, with him, I provide a tripping-lever 48, pivoted at 49 and provided with an arm 50, extending down upon lever 32. The other end of lever 48 extends out over the and of the poise-beam, so that as it rises, due 55 to the increased weight, the arm 50 is depressed, releasing latch 31, allowing bar 26 to rise, returning the counterpoise to zero and rendering the machine inoperative until again released by a coin. It will thus be 60 seen that the tripping-levers 32 and 48 will act to release the mechanism, so that the machine will be inoperative whenever the weight of the operator exceeds or falls short of any predetermined range more or less than 65 zero.

In Fig. 7 I have shown a dash-pot 51, adapted to contain any suitable fluid, as oil, and to receive a plunger 52, connected with the movable end of the poise-beam 8, so as to control the movement thereof and prevent 70 too sudden vibrations in either direction.

As shown in Fig. 9, the door 25 is provided with a window 52, which exposes the poise-beam and poise, but prevents access thereto without opening of the door. 75

The operation is as follows: The operator having opened the door and set the poise to his presumed weight then closes the door and depresses the bar 26, throwing spring-pressure on the scissor-arms 16, tending to open them when released by the locking-trigger 40. He then deposits the coin, which releases trigger 40. Upon being released the point of the variable counterpoise 14 indicates the correctness of the guess or variation, either more or less, within any predetermined limit—as, say, five pounds either way. Thus a premium is placed upon the ability of the operator to guess his own weight approximately, and if he does not do so the 90 correct weight is shown him for the cost of the coin, within the range referred to. It will be understood that the range of travel of the counterpoise and also the range of indicating-graduations of the dial 15 may be increased at will to suit different requirements of use and that the arrangement of the graduations may be changed or varied within wide limits or to coöperate with the reading of the poise-beam, as may be desired or necessary 95 to suit varying requirements.

The device may be changed or varied to suit different applications or combinations with various types of scales by the skilled mechanic; but all such changes are to be considered as within the scope of the following claims. 105

What I claim is—

1. In a coin-controlled weighing-machine, the combination of a poise-beam, a variable counterpoise connected therewith and a dial for said counterpoise whereby it is adapted to register in combination with the poise of said poise-beam, and means operatively associated with said variable counterpoise adapted to release it for operation, substantially as set forth. 110

2. In a coin-controlled weighing-machine, the combination with a pivoted poise-beam provided with a variable counterpoise constituting auxiliary indicating mechanism, and a dial for said counterpoise whereby it is adapted to register in combination with the poise of said poise-beam; of coin-controlled means operatively associated with said auxiliary indicating mechanism adapted to release it for operation, with means for reestablishing an inoperative condition of the apparatus, substantially as set forth. 115

3. In a coin-controlled weighing-machine. 120

the combination of a poise-beam, a variable counterpoise connected therewith and a dial for said counterpoise whereby it is adapted to register in combination with the poise of said beam, and means operatively associated with said variable counterpoise adapted to release it for operation, with means for reestablishing an inoperative condition of the apparatus, substantially as set forth.

10. 4. In a coin-controlled weighing-machine, the combination of a poise-beam provided with an adjustable poise, a variable counterpoise connected therewith, an indicating-dial therefor, means for controlling the position of the variable counterpoise, and releasing means actuated by a coin, substantially as set forth.

15. 5. In a coin-controlled weighing-machine, the combination of a poise-beam provided with an adjustable poise, a variable counterpoise connected therewith, an indicating-dial therefor, pivoted scissor-arms adapted to engage the variable counterpoise, and locking and releasing means therefor adapted to be

20. 25. unlocked by a coin, substantially as set forth.

6. In a coin-controlled weighing-machine, the combination of a poise-beam provided with an adjustable poise, a variable counterpoise connected therewith, an indicating-dial therefor, pivoted scissor-arms adapted to engage the variable counterpoise, and locking and releasing means therefor adapted to be

30. 35. unlocked by a coin, with means for exerting opening and closing pressure upon the scissor-arms, substantially as set forth.

7. In a coin-controlled weighing-machine, the combination of a poise-beam provided with an adjustable poise, a variable counterpoise connected therewith, an indicating-dial therefor, pivoted scissor-arms adapted to engage the variable counterpoise, locking and releasing means therefor actuated by a coin, and a depressible lever provided with springs connected with the scissor-arms, substan-

40. 45. tially as set forth.

8. In a coin-controlled weighing-machine, the combination of a poise-beam provided with an adjustable poise, a variable counterpoise connected therewith, an indicating-dial therefor, pivoted scissor-arms adapted to engage the variable counterpoise, locking and releasing means therefor adapted to be un-

50. 55. locked by a coin, a depressible lever provided with springs connected with the scissor-arms, and means for depressing said lever, substan-

tially as set forth.

9. In a coin-controlled weighing-machine, the combination of a poise-beam provided with an adjustable poise, a variable counter-

60. poise connected therewith, an indicating-dial therefor, pivoted scissor-arms adapted to engage the variable counterpoise, a limiting device therefor, means for exerting opening and closing pressure upon the scissor-arms,

65. and a pivoted coin-chute provided with a

locking-terminal adapted to engage the scissor-arms, substantially as set forth.

10. In a coin-controlled weighing-machine, the combination of a poise-beam provided with an adjustable poise, a variable counterpoise connected therewith, an indicating-dial therefor, pivoted scissor-arms adapted to engage the variable counterpoise, a limiting device therefor, a movable lever provided with opening and closing springs connected with the scissor-arms, means for depressing said lever and for holding it, and a pivoted coin-chute provided with a locking-terminal adapted to engage the scissor-arms, substantially as set forth.

15. 11. In a coin-controlled weighing-machine, the combination of a poise-beam provided with an adjustable poise, a variable counterpoise connected therewith, an indicating-dial therefor, pivoted scissor-arms adapted to engage the variable counterpoise, a limiting device therefor, a movable lever provided with opening and closing springs connected with the scissor-arms, means for depressing said lever, a holding device there- 85

for adapted to be released by the poise-beam, and a pivoted coin-chute provided with a locking-terminal adapted to engage the scissor-arms, substantially as set forth.

20. 12. In a coin-controlled weighing-machine, the combination of a poise-beam provided with an adjustable poise, a variable counterpoise connected therewith, an indicating-dial therefor, pivoted scissor-arms adapted to engage the variable counterpoise, locking and releasing means therefor adapted to be unlocked by a coin, a depressible lever provided with springs connected with the scissor-arms, a movable bar and lever provided with opening and closing springs connected with the scissor-arms, an opening-door provided with a latch adapted to engage and depress said bar and lever, a locking-lever for the bar adapted to be released by the poise-beam, and a pivoted coin-chute pro- 100

25. vided with a locking-terminal adapted to engage the scissor-arms, substantially as set forth.

30. 13. In a coin-controlled weighing-machine, the combination of a poise-beam provided with an adjustable poise, a variable counterpoise connected therewith, an indicating-dial therefor, means for controlling the position of the variable counterpoise, and releasing means actuated by a coin, with means adapted to interfere with the coin dependent on the position of the variable counterpoise, substantially as set forth.

35. 14. In a coin-controlled weighing-machine, the combination of a poise-beam provided with an adjustable poise, a variable counterpoise connected therewith, an indicating-dial therefor, pivoted scissor-arms adapted to engage the variable counterpoise, locking and releasing means therefor adapted 115

40. 125

45. 130

- 4
- to be unlocked by a coin, a depressible lever provided with springs connected with the scissor-arms, a movable bar and lever provided with opening and closing springs connected with the scissor-arms, an opening-door provided with a latch adapted to engage and depress said bar and lever, a locking-lever for the bar adapted to be released by the poise-beam, a pivoted coin-chute provided with a locking-terminal adapted to engage the scissor-arms, and a slotted baffle-plate connected with the variable counterpoise and located in the path of the coin, substantially as set forth.
- 15 15. In a machine of the class described, the combination with a poise-beam, a depressible setting-bar and means for depressing said bar; of a locking-lever therefor extending into the range of the poise-beam, substantially as set forth.
- 16 16. In a machine of the class described, the combination with a poise-beam, a depressible setting-bar and means for depressing said bar; of a locking-lever therefor extending into the range of the poise-beam, and a supplemental tripping-lever engaging the locking-lever and also extending into the range of the poise-beam, substantially as set forth.
- 20 17. In a weighing-machine, the combination with a pivoted variable counterpoise provided with a lateral abutment, of scissor-arms alongside the counterpoise adapted to engage said abutment oppositely, means for actuating said arms, and a depressible pivoted coin-chute provided with a locking-terminal adapted to engage and lock the scissor-arms, substantially as set forth.
- 25 18. In a coin-controlled weighing-machine provided with a variable counterpoise, the combination with a coin-chute, of a slotted baffle-plate connected with the counterpoise and suspended in the path of the coin, substantially as set forth.
- 30 19. The combination with a poise-beam and a variable counterpoise connected therewith provided with a positioning-abutment, a pair of pivoted scissor-arms arranged to engage said abutment to control the position of the counterpoise, and coin-controlled unlocking mechanism therefor; of a dash-pot, and a plunger mounted therein and connected with the poise-beam, substantially as set forth.
- 35 20. In a weighing-machine, the combination with a case having an exit-opening, a coin-chute arranged to deliver a coin outwardly through said exit-opening, and a pivoted variable counterpoise arranged to indicate more or less than an estimated weight; of a baffle-plate depending across the path of the coin in traveling to said exit-opening, said baffle-plate being attached to the counterpoise and provided with an opening adapted to register with the slot of the coin-chute when the counterpoise is at or about its normal position, but to interfere with the coin when the counterpoise is materially raised or lowered, substantially as set forth.
- 40 45 50 55 60 65 70
- In testimony whereof I affix my signature in presence of two witnesses.

M. HOWARD REED.
